SAFETY CONTROL FOR CUTTING MACHINES

Frederick W. Seybold, Dayton, Ohio, assignor to
 Harris-Seybold-Potter Company, Cleveland,
 Ohio, a corporation of Delaware

Application February 15, 1932, Serial No. 592,921

15 Claims. (Cl. 192—131)

This invention relates to improvements in safety controls for cutting machines, particularly paper cutters or machines for cutting other sheet materials.

5 One of the objects of the invention is the provision of means necessitating the use by the operator of both of his hands to work the knife controls until the knife has completed its descent, whereby the danger of injury to the operator's 10 hands is completely eliminated.

Another object of the invention is the automatic control of the safety means on the up-stroke of the knife so that it is unnecessary for the operator to continue to operate the controls 15 after the knife reaches the cutting stick.

Another object of the invention is the provision of means for stopping the knife mechanism almost instantly at any point in its descent should the operator release either one of the hand 20 controls.

A further object is the provision of electrical means for controlling the safety mechanism.

Other objects and features of novelty will appear as I proceed with the description of that 25 embodiment of the invention which, for the purposes of the present application, I have illustrated in the accompanying drawings, in which

Fig. 1 is a rear elevational view, somewhat diagrammatic in character, of a paper cutter 30 embodying the invention, and including a wiring diagram of the electrical control parts of the machine;

Fig. 2 is a vertical sectional detail view taken substantially on the line 2—2 of Fig. 1, showing a roller clutch which may be employed for connecting or disconnecting the knock-out cam and a rotating element of the knife mechanism;

Fig. 3 is a side elevational view of the machine;

Fig. 4 is a plan view of the machine brake and 40 its operating means;

Fig. 5 is a fragmental front elevational view of the machine showing a conventional knock-out for the knife mechanism; and

Fig. 6 is a side elevational view of the same.

45 In the drawings, the frame of the machine is indicated at 10. It supports a table 11 upon which is mounted the usual back gauge 12 which may be moved along the table by any suitable means, as, for instance, by handwheel 13 carrying a sprocket wheel upon which runs a chain 14 that is connected with the back gauge in the usual way. There is also indicated at 15 the conventional paper clamp. Upon opposite sides of the machine are vertical guides 16 within 50 which the knife bar 17 is mounted to reciprocate.

Below the table 11, and preferably in vertical alignment with the knife bar 17, there is a crank-shaft 18, which carries on its opposite ends crank pins 19 that are joined to the knife bar by connecting rods 20, so that for each revolution of the crankshaft 18 the knife makes a complete cycle of movements from the top of its stroke, or its position of rest illustrated in the drawings, downward to the cutting stick and then upward again to its position of rest, at which point the conventional knock-out mechanism stops its movement.

At the rear end of the machine there is a short shaft 21 upon which are mounted a flywheel 22 and a pulley 23. The pulley is adapted to be driven by a belt from any convenient power source, such, for example, as an electric motor. To the opposite end of the short shaft 21 there is attached one element 24 of a friction clutch, the other element 25 of which is secured to a shaft 26 aligned with the shaft 21. The shaft 26 near its opposite end carries also a brake drum 27 which is surrounded by a pair of brake shoes 28 that are pivotally mounted at 29 upon a bracket 30 bolted to the frame of the machine. At their upper ends these shoes carry rotatable pins 30 and 31 parallel to each other and to the shaft 26. A screw 32 with an operating handle 33 extends through a smooth hole in pin 31 and is threaded in pin 30. A spiral spring 34 surrounds the screw 32 between its handle 33 and the pin 31, thereby exerting pressure to draw the brake shoes together and to cause them to bear frictionally upon the brake drum 27. By adjustment of the screw, the tension of spring 34 may be varied as desired.

On the right-hand extremity of shaft 26, as viewed in Fig. 1, there is mounted a pinion 35 which meshes with a gear 36 mounted on the shaft 37. The latter shaft carries another gear 38 of smaller size which meshes with a large gear 39 on shaft 18, the latter gear carrying one of the crank pins 19 previously referred to. In this manner driving force from the relatively high speed shaft 26 is transmitted to shaft 18 at a relatively low speed and correspondingly increased torque.

Obviously, when the clutch elements 24, 25 are disengaged and the brake shoes 28 are set to frictionally engage the brake drum, the shaft 26 and the knife bar 17 will be stationary. It will also be obvious that when the clutch members 24, 25 are engaged and the brake released, the shaft 26 will turn and driving force will be transmitted to the crank-shaft 18 through the train of gears 35, 36, 38 and 39.

- In order to effect simultaneously the engagement of the clutch 24, 25 and the disengagement of the brake 27, 28, or the disengagement of the clutch and the engagement of the brake, a shipper bar 40 is slidably mounted above the shaft 26. This bar is adapted to be shifted back and forth by a hand lever 41 located at the front of the machine in a position convenient to the operator. This lever is secured to a rock shaft 42 extending from the front to the back of the machine and carrying at its rear end a short crank 43 with a yoke straddling the bar 40 between two collars 44 that are secured to the bar. There is also secured to the bar 40 at a short distance to the right of the clutch 24, 25, as viewed in Fig. 1, an arm 45 having a yoke at its lower end straddling a collar 46 which is slidably keyed to the shaft 26. This collar carries a wedge pin or finger 47 that is adapted to set the clutch when shifted to the left, as viewed in Fig. 1. The details of the clutch construction are not herein disclosed, as the present invention is not concerned therewith.
- The shipper bar 40 extends above the brake drum 27 between the upper ends of the brake shoes 28. Beyond the bracket 48 in which the bar 40 is slidably mounted, the latter has attached thereto a collar 49 having a pair of wedge fingers 50 integrally attached thereto and adapted to spread the brake shoes 28 in opposition to the force of spring 34 when the shipper bar 40 is moved toward the left in Fig. 1, thereby releasing the brake. The collar 49 also has formed in one side thereof a V-shaped notch 51 which is adapted to receive a roller detent 52 when the shipper bar is in its normal inoperative position illustrated in the drawings. The detent 52 is resiliently pressed toward the collar 49 by a spring mounted in a cylinder 53, or otherwise, riding up the rear side of the notch 51 onto a flat plate 54 integrally formed upon the collar 49, when the bar 40 is shifted toward the left. The detent 52 prevents any accidental movement of the shipper bar 40 toward the left, and hence is a safety device.
- In Figs. 5 and 6 I have shown, somewhat diagrammatically, a conventional knock-out arrangement for stopping the knife mechanism when the knife bar reaches its position of rest. On the righthand end of crank-shaft 18, as viewed from the front of the machine in Fig. 5, there is a crank plate 90 carrying one of the cranks 19. This plate has a knock-out cam 91 on its periphery. Secured to the forward end of rock shaft 42, or to the handle 41 on that shaft, there is a knock-out arm 92, upon the lower extremity of which is an anti-friction roller 93 which is adapted to be engaged by the cam 91 when the arm 92 is swung the proper distance toward the right from the position indicated in Fig. 5.
- All of the parts of the machine thus far described are known and in common use. The added features constituting the present invention either per se or in combination with the known features of the machine will now be described.
- On the shipper bar 40 there is secured at the proper position a depending dog 55 having an anti-friction roller 56 thereon. This roller 56 is adapted to be shifted toward the right by a knock-out cam 57 when the shipper bar is in its operative position to the left of that shown in Fig. 1, and also when the knock-out cam 57 is locked to the shaft 26. When the cam is not locked to the shaft, the latter turns freely within the cam, gravity acting upon the wider and

heavier part of the cam to hold it against rotation. Means are provided, however, for locking the cam 57 to the shaft at times when it is desirable or necessary for the machine to stop, and in the present instance this means takes the form of a roller clutch shown in detail in Fig. 2. This roller clutch comprises a hardened collar 58 which is keyed to shaft 26. Opposite this collar, the clutch casing, which is free to turn with respect to shaft 26 and is secured to or integral with knock-out cam 57, carries two segments 59 and 60 having flat hardened surfaces facing the collar. Coil springs 61 tend to force hardened rollers 62 into position between the sectors 59 and 60 and the collar 58 so as to lock these parts together. The action of the coil springs 61 may be opposed, however, by slide bars 63. These bars are adapted to be moved inwardly toward the springs by screws 64 which are threaded in the housing of the clutch and bear at their inner extremities upon the outer ends of the slide bars 63. These bars near their outer ends are engaged by pins 65 by means of which they are steadied and guided. The screws 64 are provided with outwardly projecting extensions 100 which are clamped within links 66 outside the casing of the clutch. To these links are pivotally attached connecting rods or links 67. The latter are pivotally connected to lateral extensions 68 upon a collar 69 free to turn upon the shaft 26.

A yoke on the upper end of bell-crank lever 70 runs in the collar 69. This lever is pivoted at 72 on a bracket 73 attached to the frame of the machine. The other arm of the lever is connected to a soft iron core movable within a solenoid 74 which, when energized, holds the lever 70 in the position illustrated in Fig. 1. A coil spring 75 works in opposition to the solenoid and acts to pull the lever toward the right when the solenoid is deenergized. In the position of the parts illustrated in the drawings, the screws 64 are turned to their inward limit of motion, pushing the slide bars 63 inwardly to force the rollers 62 out of locking engagement, thereby leaving the collar 58 free to turn within the sectors 59 and 60. When the solenoid 74 is deenergized, however, the spring 75 immediately pulls the lever 70 to the right, causing the links 67 and 66 to turn the screws 64 so as to back them off, whereupon the springs 61 force the rollers 62 into jamming position between the collar 58 and the sectors 59 and 60. The knock-out cam 57 is then locked to the collar 58 which is keyed to the shaft, and acts immediately to force the dog 55 toward the right to disconnect the clutch 24, 25 and set brake 27, 28, thereby stopping the knife travel.

Now, while it is appreciated that mechanical means might be employed for moving the lever 70 upon its pivot to control the roller clutch and thus effect the operation of the knock-out cam at the proper time, particularly for stopping the knife at the top of its stroke, I prefer to employ electrical means now to be described, this means also lending itself especially well to the purpose of operating the knock-out as a safety control during the descent of the knife on the cutting stroke.

Referring now to Fig. 1, 80 and 81 are electric conductors for delivering current to the solenoid 74. Conductor 81 leads directly to the solenoid 14, while conductor 80 is connected with the solenoid through one of two parallel circuits. The first of these parallel circuits includes a conductor 82, a push button or other switch 83 preferably mounted upon the handle of lever 41, a second 15

push button or other switch 84 located at a convenient point on the front of the machine separated from the switch 83 so that it is impossible for the operator to close both switches with one hand, and a conductor 85 running to the solenoid. The other parallel circuit includes a conductor 86 extending to a switch 87 of the push button type mounted in a housing adjacent the crankshaft 18, and a conductor 88 extending from the other binding post of the switch to conductor 85. The switch 87 is closed during the up-stroke of the knife bar by a cam 89 on shaft 18, and is open throughout the down-stroke of the knife bar.

It will be obvious that if the lever 41 is so positioned that it would be impossible for the operator to maintain his grip upon it with one hand and place his other hand in danger of being cut by the descending knife, then the switch 84 may be dispensed with, but usually it will not be desirable to so locate the lever. It will also be obvious that both of the switches 83 and 84 may be mounted upon the lever 41 if they are positioned far enough apart to require both hands of the operator to close them.

The operation of the knife mechanism and its safety control will be apparent to those skilled in the art from the foregoing description of its parts. When the knife bar is in its position of rest, the cam 89 will be in position to hold the switch 87 closed. A further slight rotation of shaft 18 in the direction indicated by the arrow, however, will serve to open the switch 87. While this switch is closed, the electromagnet 74 will be energized by current passing through the conductors 80 and 86, switch 87, conductors 88 and 85 to the electromagnet and back through conductor 81 to the line, the safety knock-out mechanism therefore being in the condition illustrated in Fig. 1. Now, when the operator desires to set the knife mechanism in operation, he grasps the lever 41 with his right hand, being careful to close the switch 83 at the same time, and with his left hand he closes the switch 84. An electric circuit is then completed through conductors 80 and 82, switches 83 and 84, and conductor 85 to solenoid 74 and back through conductor 81 to the line, thereby maintaining the safety knock-out in the position of Fig. 1 after the cam 89 moves far enough to open switch 87. The operator then depresses the outer end of lever 41 to shift shipper bar 40 toward the left in Fig. 1, releasing the brake 27, 28 and engaging the clutch 24, 25. The shaft 26 immediately receives driving force and operates through the train of gears 35, 36, 38 and 39 to turn crank-shaft 18. The shaft 26 rotates freely within knock-out cam 57. The knife bar then starts downwardly. If during its descent the operator either intentionally or accidentally permits either one of the switches 83 and 84 to open, the solenoid 74 is deenergized, the spring 75 pulls lever 70 to the right, and the screws 64 of the roller clutch are backed off, permitting the springs 61 to move the rollers 62 into wedging position, whereupon the knock-out cam 57 is locked to the shaft 26 and turns to force dog 55 to the right, thereby disengaging the clutch 24, 25 and setting brake 27, 28 so that the motion of the knife bar is stopped almost instantaneously, or as soon as the shaft 26 has turned through one-half a revolution. The speed reduction between shafts 26 and 18 being quite considerable, it is apparent that one-half a revolution of shaft 26 corresponds to a very small movement of shaft 18 and a correspondingly short movement of the

knife. For instance, if the speed reduction be 10 to 1, one-half a revolution of the shaft 26 would correspond to a descent of the knife through one-tenth of the distance from the position of rest to the cutting stick, and such a short space of time 80 would be insufficient to enable the operator to get either one of his hands into a position of danger. Should the knife be stopped in its descent by the safety means just described, it is then necessary for the operator to proceed in the same manner 85 as above described in order to again start the knife upon its descent. After the cut is made, that is, after the knife has touched the cutting stick, the operator may permit both of the switches 83 and 84 to open. This will not 90 interrupt the further travel of the knife for the reason that by that time the cam 89 on the crank-shaft 18 has closed switch 87, thereby maintaining the circuit through solenoid 74 by way of conductors 80 and 86, switch 87, conductors 88 and 85, solenoid 74 and conductor 81. The cam 89 covers a trifle more than one-half 95 the periphery of shaft 18, corresponding to the full upward travel of the knife and insuring the closing of the switch 87 while the knife is in its 100 position of rest. When the knife reaches the upper end of its stroke, the cam 91 on plate 90 engages anti-friction roller 93 and shifts it toward the left, as viewed in Fig. 5, thereby imparting movement to shaft 42 through a sufficient 105 angle to shift the shipper bar 40 back to its original or inoperative position, which causes the finger 47 to be withdrawn from engagement with the actuating lever of clutch 24, 25, and causing the wedging fingers 50 to be withdrawn from engagement with the brake shoes 28, thereby permitting the spring 34 to again set the brake. The parts will remain in this condition until the operator again depresses the lever 41 for the purpose of making another cut.

While I prefer to employ the novel electrically controlled knock-out mechanism disclosed herein as a safety device exclusively, relying upon the usual mechanical knock-out mechanism disclosed in Figs. 5 and 6 for stopping the knife movement 120 at the position of rest, that is to say, the upper end of the knife stroke, it will be apparent that it is quite possible to eliminate the mechanical knock-out mechanism, if desired, and employ the electrically operated mechanism for stopping the 125 knife in its position of rest, as well as for the safety control purpose hereinbefore described. In order to effect this result, it is only necessary to shorten the cam 89 slightly so that it will open switch 87 when the knife reaches its top position. Under such circumstances, the coil 74 will be deenergized and the spring 75 will act to cause the engagement of the roller clutch, thereby operating the knock-out cam 57 and stopping the knife mechanism. When the machine is set up in 130 this way, the first action occurring after the operator closes the switches 83 and 84 preparatory to depressing the lever 41 will be the shifting of lever 70 toward the left in response to the energization of coil 74, thereby disengaging 135 cam 57 from shaft 26, and permitting the shaft to rotate freely within the cam. In other respects, the functioning of the safety knock-out mechanism will be the same as previously described.

Inasmuch as my electric control as herein disclosed is merely added to the mechanical control of the machine, it is entirely possible to disable the electrical control whenever conditions or the preference of the operator may make that desirable.

All that it is necessary to do in that event is to unhook one end of spring 75. Thereafter the knock-out 57 will hang loosely upon the shaft 26 at all times, whether or not the buttons 83 and 84 are depressed or the switch 87 closed. In fact the electric current to line 80, 81 may be turned off.

In the foregoing description I have necessarily gone somewhat into detail in order to explain fully the particular embodiments of the invention herein illustrated, but I desire it to be understood that such detail disclosures are not to be construed as amounting to limitations except as they may be included in the appended claims.

15 Having thus described my invention, I claim:

1. In a cutting machine, power driven mechanism for causing the cutting knife to descend from its position of rest to make the cut and then rise again to its position of rest, a hand control member for setting said mechanism into operation, a separate control member for actuation by the other hand of the operator, means for interrupting the action of said knife mechanism promptly upon the removal of either of the operator's hands from said control members during the descent of the knife, and means for interrupting the action of said knife mechanism when the knife upon its ascending movement arrives again at the position of rest.

20 2. In a cutting machine, power driven mechanism for causing the cutting knife to descend from its position of rest to make the cut and then rise again to its position of rest, a hand control member for setting said mechanism into operation, means tending to interrupt the action of said knife mechanism, manual control means adapted to interfere with the action of said interrupting means during the descent of the knife, and means associated with the knife mechanism for automatically interfering with the action of said interrupting means during the rising movement of the knife.

25 3. In a cutting machine, power driven mechanism for causing the cutting knife to descend from its position of rest to make the cut and then rise again to its position of rest, a hand control member for setting said mechanism into operation, means tending to interrupt the action of said knife mechanism, separate controls for the two hands of the operator adapted to interfere with the action of said interrupting means during the descent of the knife, and means associated with the knife mechanism for automatically interfering with the action of said interrupting means during the rising movement of the knife.

30 4. In a cutting machine, power driven mechanism for causing the cutting knife to descend from its position of rest to make the cut and then rise again to its position of rest, means for setting said mechanism into operation, means tending to interrupt the action of said knife mechanism, and electrical means comprising two hand switches for maintaining said interrupting means ineffective during the descent of the knife and comprising a switch automatically actuated by the knife mechanism during the upward movement of the knife for maintaining the said interrupting means ineffective.

35 5. In a cutting machine, power driven mechanism for causing the cutting knife to descend from its position of rest to make the cut and then rise again to its position of rest, means for starting said mechanism and maintaining it in operation until the knife descends to make the cut

and returns to said position of rest, said means comprising an electrical circuit, and manually operated control means for holding the circuit closed until the descent of the knife is completed, and automatically operated means for holding the circuit closed during the upward travel only of the knife.

6. In a cutting machine, power driven mechanism for causing the cutting knife to descend from its position of rest to make the cut and then rise again to its position of rest, means for starting said mechanism and maintaining it in operation until the knife descends to make the cut and returns to said position of rest, said means comprising an electric circuit, two separated manually operated switches for holding the circuit closed until the descent of the knife is completed, and automatically operated means for holding the circuit closed during the upward travel only of the knife.

10 7. In a cutting machine, a knife, a crank-shaft operatively connected with said knife for causing the latter to descend from its position of rest, make the cut, and return to its position of rest, all during one revolution of said crank-shaft, means for driving said crank-shaft comprising a second shaft turning at a relatively high rate of speed, control means for starting and stopping said second named shaft, and means associated with said second named shaft for operating said control means to stop the knife mechanism before said high speed shaft has completed one revolution whenever the operator removes his hand from said control means during the descent of the knife.

110 8. In a cutting machine, a knife, a crank-shaft operatively connected with said knife for causing the latter to descend from its position of rest, make the cut, and return to its position of rest all during one revolution of said crank-shaft, means for driving said crank-shaft comprising a second shaft turning at a relatively high rate of speed, control means for starting and stopping said second named shaft, a knock-out operatively associated with said control means, means operatively associated with said second named shaft for actuating said knock-out to cause the control means to stop the knife mechanism, said last named means being actuated to operate said knock-out whenever the operator removes his hand from said control means during the downward travel of the knife.

115 9. In a cutting machine, a knife, a crank-shaft operatively connected with said knife for causing the latter to descend from its position of rest, make the cut, and return to its position of rest all during one revolution of said crank-shaft, means for driving said crank-shaft comprising a second shaft turning at a relatively high rate of speed, control means for starting and stopping said second named shaft, a knock-out operatively associated with said control means, means operatively associated with said second named shaft for actuating said knock-out to cause the control means to stop the knife mechanism, said last named means being actuated to operate said knock-out whenever the operator removes his hand from said control means during the downward travel of the knife and being actuated automatically at the end of the upward travel of the knife.

120 10. In a cutting machine, a knife, a crank-shaft operatively connected with said knife for causing the latter to descend from its position of rest, make the cut, and return to its position of rest

- all during one revolution of said crank-shaft, means for driving said crank-shaft comprising a second shaft turning at a relatively high rate of speed, control means for starting and stopping said second named shaft, a knock-out operatively associated with said control means, means operatively associated with said second named shaft for actuating said knock-out to cause the control means to stop the knife mechanism, and electrical means for controlling said last named means, said electrical means including a switch to be held in a given position by the operator until the knife has completed its descent. 10
11. In a cutting machine, a knife, a crank-shaft operatively connected with said knife for causing the latter to descend from its position of rest, make the cut, and return to its position of rest all during one revolution of said crank-shaft, means for driving said crank-shaft comprising a second shaft turning at a relatively high rate of speed, control means for starting and stopping said second named shaft, a knock-out operatively associated with said control means, means operatively associated with said second named shaft for actuating said knock-out to cause the control means to stop the knife mechanism, and electrical means for controlling said last named means, said electrical means including a switch to be held in a given position by the operator until the knife has completed its descent and including also a switch automatically held by the knife mechanism in a given position during the upward travel of the knife. 20
12. In a cutting machine, power driven mechanism for causing the cutting knife to descend from its position of rest to make the cut and then rise again to its position of rest, means for starting said mechanism and maintaining it in operation until the knife descends to make the cut and returns to said position of rest, said means comprising an electric circuit, manually operated means for holding the circuit closed until the descent of the knife is completed, and automatically operated means in shunt with said manually operated means, said automatically 30
- operated means serving to hold the circuit closed during the upward travel of the knife. 35
13. In a cutting machine, a knife, power driven mechanism for causing the knife to descend from its position of rest, make the cut, and move upwardly again to its position of rest, a longitudinally movable shipper bar for starting and stopping said mechanism, a dog on said bar, said mechanism comprising a driven shaft located near said shipper bar, a knock-out loosely mounted on said shaft, a clutch between said shaft and knock-out, and means for setting said clutch to cause said knock-out to shift said dog and thereby move said shipper bar to stop said mechanism. 40
14. In a cutting machine, a knife, power driven mechanism for causing the knife to descend from its position of rest, make the cut, and move upwardly again to its position of rest, a longitudinally movable shipper bar for starting and stopping said mechanism, a dog on said bar, said mechanism comprising a driven shaft located near said shipper bar, a knock-out loosely mounted on said shaft, a clutch between said shaft and knock-out, means for setting said clutch to cause said knock-out to shift said dog, and electrical 45 means for maintaining said clutch setting means normally inoperative. 50
15. In a cutting machine, a knife, power driven mechanism for causing the knife to descend from its position of rest, make the cut, and move upwardly again to its position of rest, a shipper bar for starting and stopping said mechanism, a dog on said bar, said mechanism comprising a driven shaft located near said shipper bar, a knock-out loosely mounted on said shaft, a clutch between said shaft and knock-out, means for setting said clutch to cause said knock-out to shift said dog, electrical means for maintaining said clutch setting means inoperative, said electrical means comprising a manually operable 55 switch effective during the downward travel of the knife and an automatic switch effective during the upward travel of the knife back to said position of rest. 60
